INVENTOR

Tom D. Anderson

ATTORNEY

UNITED STATES PATENT OFFICE.

TOM D. ANDERSON, OF SAN JOSE, CALIFORNIA.

BED.

Application filed May 13, 1922. Serial No. 560,644.

To all whom it may concern:

Be it known that I, TOM D. ANDERSON, a citizen of the United States, and resident of San Jose, in the county of Santa Clara and State of California, have invented certain new and useful Improvements in Beds, of which the following is a specification.

My invention relates to a type of folding cot or bed particularly adapted for use by campers and tourists.

One of the objects of my invention is to provide a bed of the character indicated which is entirely made of metal thus assuring a bed of strong rigid construction.

Another object is to provide means whereby the bed may be securely locked in an open position; also means are provided for securing a strong, flexible spring construction which is extremely resilient while at the same time holding its shape.

Still another object is to provide a resilient spring construction which can be readily rolled up into a small, compact bundle.

Furthermore it is an object of my invention to provide a bed of the character indicated which is simple in form, easy to manufacture and assemble, being of few parts and highly efficient in its practical application as well as being readily folded and rolled into an extremely small, compact bundle.

In the drawing:—

Figure 1 is a perspective view of my improved folding bed, in an inverted position, showing the relative positions of its several parts.

Figure 2 is an enlarged perspective view of the side locking mechanism, parts broken away.

Figure 3 is an enlarged cross-section taken through one of the end assemblies when folded ready to roll up on a line along the longitudinal axis of the bed.

Figure 4 is an end view of the bed showing the legs being folded in upon the end piece itself.

Figure 5 is a perspective view showing the side member folded up into the leg member.

Figure 6 is a side view showing the spring element locked to the chain element.

Referring more particularly to the drawing, I show at 1—2 two angle iron end pieces to which are pivotally mounted at points 3—4—5—6 the leg members 7—8—9—10 respectively as shown, these members being formed of similar angle iron construction having their lower ends flared outwardly as at 11—12—13—14 to form foot members therefor as shown and all being slightly shorter than members 1—2.

Pivotally mounted upon leg members 7—8—9—10 are flat iron brace members 12—13—14—15 which have their outer ends formed into hooks which snap over pins 38—39—40—41 on end members 1—2 respectively as shown. These brace pieces when in place upon their respective pins serve to hold the legs rigidly in place the same folding up into their respective leg members as shown in Figure 4.

At 16 is shown an angle iron side piece which is approximately as long as the end pieces 1—2, the same having a notch 17 in the outer end thereof to engage a pin 18 set into a second side member 19 both being pivotally mounted upon their respective leg members 7—9 at points 20—21 as shown.

Upon leg member 8 is pivotally mounted at 22 a side member 23 which is similar to side member 19 in that it is the same length and has the pin 18 set therein as shown, while leg member 10 has a side member 24 pivotally mounted thereon as at 25 the same being provided with the slot 17 as is side member 16, this construction locating said pins and slots in opposed relation to each other as shown.

Slidably mounted upon side members 19—24 by means of a pin 26 working in a slot 27 is an angle iron member 28, the end 29 of which passes through orifices 30 in the members 19—24 as shown. The side members 16—23 have similar orifices as 31 so located that when the two pairs of side members 16—19 and 23—24 are brought on the same plane, the end 29 of sliding members 28 passes through orifices 30—31 thus locking the same rigidly together.

Mounted upon end elements 1—2 are a series of springs 32—32 having a number of lines of chains as 33 secured thereto and running parallel with the side members of

the bed as shown. Passing through a link of each row of chains and at right angles therewith and secured to said chains at each end by a collar 34 are a series of resilient 5 wire elements 35 which serve to hold the chains in a spread position as well as giving greater resiliency to the whole bed.

When it is necessary to fold up the bed the foot is pressed down upon the inverted 10 side members and the sliding member 28 is pulled out from the slots 30—31 thus disengaging the two pairs of side members. Member 23 is then folded up into the leg 8, the brace 13 is unhooked and also folded up 15 as shown in Figure 4, the leg is then swung inwardly until it parallels end member 1. The side member 16, brace 12 and leg 7 is now folded in the same manner and collapses upon the other leg assembly in such 20 a position that it is all securely held together in as small a space as possible in the relative positions shown in the cross-section of Figure 3. The other side members 19—24, legs 9—10 and braces 14—15 are 25 folded in the same manner and then the two end assemblies are rolled up with the chains 33 and resilient elements 35, making a small, compact bundle.

At 36 is shown a member secured to the 30 side member 23 and having an upstanding portion 37 formed thereon which acts as a guide for side member 24 when the bed is being set up. The member 36 preventing the members 23—24 from shifting side- 35 ways when the strain of the springs being extended is exerted thereupon, thus taking this side strain from the bolts 22—24 and allowing the bed to be set up quickly and easily without danger of breaking at the 40 said points of support for the side members 23—24 to the legs 8—10. A similar guide is also placed upon side member 16, the same not showing in the drawing.

Thus it is seen that I have provided a 45 bed which is strong, rigid when extended, of few parts and easily and quickly disassembled when not in use and rolled up, into a very small, compact bundle easily carried by tourists or campers. By constructing the fabric as described the same 50 will never become tangled but will always flatten out without effort because the resilient elements 35 while they provide a certain degree of flexibility in the fabric also persist in reassuming their normal straight condition. The chains being spaced at all 55 times cannot become entangled and the elements 35 offer no opportunity for entanglement such as is offered by the usual coiled spring.

It is to be understood, of course, that while I have herein shown and described one particular embodiment of my invention that changes may be made in form, construction, materials used as well as in manner of 60

arrangement and relation of parts therein as is allowed by the scope of the appended claims.

I claim:

1. A one-piece folding cot comprising a 70 pair of end members L shaped in cross-section, a fabric supported thereby, a leg L shaped in cross-section pivotally mounted upon each end of each end member, the two legs on each end member folding one into 75 the other and into the end member into parallel relationship to each other, and a side bar pivotally mounted on each leg and L shaped in cross-section whereby to fold into the leg upon which it is mounted and into 80 the end member, the free ends of the side bars on each pair of side legs being adapted to engage each other, and means for locking said ends in rigid relation to each other when engaged. 85

2. A one-piece folding cot comprising a pair of end members L shaped in cross-section, a fabric supported thereby, a leg L shaped in cross-section pivotally mounted upon each end of each end member, the two 90 legs on each end member folding one into the other and into the end member into parallel relationship to each other, and a side bar pivotally mounted on each leg and L shaped in cross-section whereby to fold into 95 the leg upon which it is mounted and into the end member, the side bar on one leg having a notch formed in the end thereof and overlapping the side bar on the corresponding side leg, a pin on the overlapping 100 side bar to engage said notch, and means for locking the overlapping portions in rigid relation to each other.

3. A one-piece folding cot comprising a pair of end members L shaped in cross-section, a fabric supported thereby, a leg L shaped in cross-section pivotally mounted upon each end of each end member, the two legs on each end member folding one into 105 the other and into the end member into parallel relationship to each other, and a side bar pivotally mounted on each leg and L shaped in cross-section whereby to fold into the leg upon which it is mounted and into 110 the end member, the side bar on one leg having a notch formed in the end thereof and overlapping the side bar on the corresponding side leg, a pin on the overlapping side bar to engage said notch, one of each pair 115 of side bars having a slot formed therein and the other having a bar slidably mounted thereon to engage said slot. 120

4. A one-piece folding cot comprising a pair of end members L shaped in cross-section, a fabric supported thereby, a leg L shaped in cross-section pivotally mounted upon each end of each end member, the two legs on each end member folding one into the other and into the end member 125 into parallel relationship to each other, and 130

a side bar pivotally mounted on each leg and L shaped in cross-section whereby to fold into the leg upon which it is mounted and into the end member, one of said side bars having a notch formed in the end thereof and a bar slidably mounted transversely thereof and adjacent the end thereof, and the other bar having a pin extending from the outside thereof and adjacent the end thereof, and having a slot formed therein 10 adjacent its outer end.

TOM D. ANDERSON.
